UNITED STATES PATENT OFFICE

2,441,781

ROTARY BRUSH ASSEMBLY

Joseph P. Vanuch, Lakewood, Ohio

Application February 24, 1945, Serial No. 579,525

2 Claims. (Cl. 15—179)

1

This invention has reference to rotary brushes and one object is to provide means whereby brushes of this nature may be manufactured with greater rapidity than heretofore.

Another object of the invention is to provide a rotary brush of such a substantial construction that it may be operated at a much greater speed.

A further object of the invention is to provide face plates for a rotary brush so formed that it 10 will be impossible for relative movement between the plates and their brush segments.

Other features and advantages will become more readily apparent from the following description and the accompanying illustrative 15 drawings in which:

Figure 1 is an elevational view of a rotary brush formed in accordance with my invention,

Figure 2 is a transverse sectional view thereof,

Figure 3 is a detail sectional view of a male 20 face plate,

Figure 4 is a similar view of a female face plate,

Figure 5 is an edge view thereof,

Figure 6 is a transverse sectional view of Figure 5, and

Figure 7 is a detail sectional view of Figure 1.

In the drawings and specification like reference characters indicate like parts and in which 10, is a brush formed according to my invention and which comprises a male face plate 11, and a female face plate 12. The plate 11, is provided with a pressed in central portion 13, having an arbor opening 14, in the center thereof. The rim portion 15, of this plate is provided with a series of equi-distant struck out tongues 16 and 16', the purpose of which will presently be explained. The walls 15 and 17, are parallel with one another and the joining wall 17, has struck therefrom a series of equally spaced tongues 19. The female plate 12, is provided with a central opening 20, the diameter of which is equal to that of the struck in portion 13, of plate 11, and its outside diameter is the same as that of plate 11. The plate 12, is provided with a series of equally spaced struck out tongues 21, and between these tongues are provided equally spaced slots 22.

In assembling the parts of the device the circular brush 23, is placed between the plates 11 and 12, and then put under pressure, causing the tongues 16, to penetrate the body 24, of the brush bristles and project through slots 22, in member 12, and pressed down at right angles to securely bind members 11 and 12, together. At

2

the same time lugs 21, of the plate 12, penetrate the member 24, only and rest upon the inner face 25, of the rim 15, of member 11. The same operation turns the tongues 19, out upon the inclined wall 18, and into engagement with the inner face 26, of member 12, thus the brush is completed.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters 20 Patent is:

1. A rotary brush comprising a hub disk having a centrally disposed arbor receiving opening therein, a bristle clamping flange concentric with the periphery of the hub disk, said flange being offset to one side of the general plane of the hub disk, radially spaced tongues struck from the disk at its junction with the flange, said tongues being bent back upon themselves to form an annular row of supporting lugs concentric about the central opening in the disk, an annular row of bristle tufts radially disposed on the face of the flange facing the hub, a clamping ring supported on the lugs in concentric relation with the flange for clamping the bristle tufts against the flange, said ring having an annular row of radially spaced openings therein and ring clamping tongues struck from the flange and projecting through the openings in the ring, the free ends of said tongues being clinched over the outer face of the clamping ring to clamp the bristle tufts in place.

2. A rotary brush comprising a hub disk having a centrally disposed arbor receiving opening therein, a bristle clamping flange concentric with the periphery of the hub disk, said flange being offset to one side of the general plane of its junction with the flange, said tongues being bent back upon themselves to form an annular row of supporting lugs concentric about the central opening in the disk, an annular row of bristle tufts radially disposed on the face of the flange facing the hub, a clamping ring supported on the lugs in concentric relation with the flange for clamping the bristle tufts against the flange, said ring having an annular row of radially

spaced openings therein, ring clamping tongues struck from the flange and projecting through the openings in the ring, the free ends of said tongues being clinched over the outer face of the clamping ring to clamp the bristle tufts in place, and an annular row of spacing tongues struck from the clamping ring and extending inwardly through the bristle tufts to engage the flange and hold the flange and ring in spaced parallel relation.

JOSEPH P. VANUCH.
